UNITED STATES PATENT OFFICE

CHARLES I. LONGENECKER, OF WAUWATOSA, WISCONSIN, ASSIGNOR TO CHAIN BELT COMPANY, OF MILWAUKEE, WISCONSIN, A CORPORATION OF WISCONSIN

PLUNGER PUMP

Application filed June 19, 1930. Serial No. 462,281.

This invention relates to plunger pumps, and more particularly to pumps of this type which are intended for use by building, paving and other contractors, in the field, for pumping dirty water, mud and slimes, and has for one of its objects the provision of improved lubrication and packing for the working surfaces of the cylinders and plungers of such pumps.

10 The lubrication of pumps of this character has proven to be quite a problem, due to the nature of the materials being pumped, and to the fact that the pumps receive little or no attention on the part of the operator. 15 The water which they are called upon to force nearly always contains some sand or other gritty, abrasive substance, and they are in many cases employed in the pumping of extremely muddy water containing high percentages of solids. Under such conditions, the working surfaces of the cylinders and plungers are of necessity subject to relatively great wear, and it is of extreme importance to provide as efficient lubrication and 25 packing for these surfaces as is possible.

To this end, the present invention comprises the use of a substantially closed hollow plunger, which may contain oil or other suitable lubricant, which will be automatically fed to the cylinder walls without attention on the part of the operator, other than to replenish the supply of lubricant within the plunger when it becomes exhausted. The said hollow plunger is inverted, or disposed with its head downwardly, and comprises two telescoping members adjustably secured together, with yieldable packing between them for engaging the cylinder walls to prevent the water from working up past the plunger, and the lubricant from working down into the pump chamber. The top wall of the upper of the two telescoping plunger members is provided with a central opening to accommodate the connecting rod which moves the plunger, and in order to conserve any lubricant which may splash out through this opening, as it sometimes does in actual operation, the said top wall is inclined downwardly in all directions 45 from the said opening, so that such splashed

lubricant will run to the outer periphery of the plunger. The upper portion of the cylinder is enlarged or flared outwardly to provide a space which may receive this oil as the plunger works up and down, and supply it to the working walls of the cylinder as needed.

Referring to the accompanying drawings, in which one form of the invention is illustrated, and in which like reference characters designate like parts in all the views:

Figure 1 is a diagrammatic plan view of a portable plunger pump of the type above described, and intended for road work or other similar use;

Fig. 2 is a diagrammatic side elevational view of the parts shown in Fig. 1;

Fig. 3 is an enlarged vertical sectional view through the pump cylinder, plunger and working chamber; and

Fig. 4 is a cross sectional view, taken approximately on the plane indicated by the line 4-4, of Fig. 3.

In the said drawings, 10 indicates a frame or chassis, mounted upon the road wheels 11, and carrying the working chamber or water box 12, which receives the lower end of the vertical pump cylinder 13. An internal combustion engine or other source of power is enclosed within a housing 14, and is connected by suitable gearing within the gear casing 15 to the crank shaft 16, carrying the crank 17, which is connected through the pitman 18 with the rocker 19. The connecting rod 20 is pivoted at one end to the said rocker arm 19, and at its other end to the plunger 21. An inlet valve housing 22, containing the inlet valve 23, is secured to one end of the water box or working chamber 12, and the supply conduit 24 leads to the said valve housing 22, as will be clear from Fig. 3. The outlet valve housing 25, containing the outlet valve 26, is secured to the opposite end portion of the water box, and discharges into the outlet conduit 27. The usual air cushion tank or chamber 28 is preferably provided, being connected to the discharge line by the pipe 29 leading from the outlet valve housing 25, substantially as shown.

The plunger 21, which constitutes an im-

portant feature of the invention, comprises a piston member 30, having a working head 31, and a hollow skirt portion 32 of somewhat lesser diameter than the said head.

- 5 The said skirt portion is provided with the aligned bearings 33, having the bores 34, which receive the piston pin 35, by means of which the connecting rod 20 is pivoted to the plunger. The said pin 35 is preferably 10 held against rotation by a set screw 36, and transverse lubricant passages 37 lead into the said bores 34.

An inverted hollow follower 40 telescopes over the skirt portion 32 of the piston member 30, and is detachably and adjustably secured by bolts or other suitable fastenings 41, as will be clear from the drawings. The inner periphery of the said follower is provided with a circumferential lubricant 20 groove or passage 42, which in the assembled positions of the parts comes opposite to the ends of the piston pin bores 34, and radial lubricant passages 43 lead from the said circumferential groove 42 to the outer periphery of the follower. An asbestos rope or other similar compressible packing 44 is interposed between the lower end of the follower and the working head 31 of the piston member, and since the follower is adjustable 25 relative to the piston member, as above explained, wear upon the said packing may be taken up by screwing down on the bolts 41, as will be readily understood.

The top wall 45 of the follower is provided with a central opening 46 to accommodate the connecting rod 20, and since this opening must of necessity be somewhat larger than the said rod to allow for oscillation of the latter, it frequently happens 40 in actual practice that some of the lubricant which is contained in the hollow plunger splashes out through the said opening and on to the exterior surface of the said top wall. In order to conserve this lubricant 45 and feed it to the working surfaces of the plunger and cylinder, the said top wall is inclined slightly downwardly in all directions from the opening 46, or, in other words, is made slightly conical, so that any lubricant 50 which may splash out through the said opening will be caused to flow by gravity toward the outer periphery of the plunger, and will be fed to the working surfaces of the plunger and cylinder walls.

55 In many cases, quite a considerable amount of lubricant finds its way to the upper surface of the plunger, and in order to further facilitate the use of this lubricant, it is preferred to enlarge or flare outwardly 60 the upper portion of the cylinder, as indicated at 47, thus providing a space greater than the normal clearance between the plunger and cylinder, into which the said lubricant may flow during the upper portion 65 of the stroke of the plunger, and from

which it may flow downwardly on the cylinder walls, when the plunger is below the said enlargement.

The top wall of the plunger is provided with an opening 48, through which lubricant 70 may be introduced into the interior, which opening is normally closed by a threaded plug 49. The connecting rod 20 may be provided with a deflector 50 for directing the lubricant which splashes through the opening 46 downwardly to the inclined top wall 45, as will be readily understood.

In use, the hollow plunger 21 is partially filled with suitable lubricant through the filling opening 48, at least up to the level 80 of the radial lubricant passages 43, and this lubricant finds its way during the operation of the pump through the passages 37 into the bores 34, and thence through the passages 42 and 43 to the contacting surfaces of the plunger and cylinder walls. The lubricant within the plunger also lubricates the bearing surfaces of the connecting rod 20 and piston pin 35. Any lubricant which splashes through the opening 46, due to reciprocation of the plunger or the vibration 90 of the apparatus, will be fed to the space formed by the offset 47 and to the cylinder walls, as above described.

The valves 23 and 26, as well as their 95 housings 22 and 25, are preferably identical, to reduce the cost of manufacture.

While one form of the invention has been illustrated and described, it is obvious that those skilled in the art may vary the details of construction, as well as the precise arrangements of parts, without departing from the spirit of the invention, and therefore it is not wished to be limited to the above disclosure, except as may be required 105 by the claims.

What is claimed is:—

1. A self-lubricating plunger for pumps and the like, comprising a hollow piston member having a working head and piston pin bearings provided with passages adapted to conduct lubricant to the bores thereof; a hollow follower telescoping over said piston member to provide a substantially closed hollow plunger adapted to contain lubricant, said follower having lubricant passages affording communication between the bores of said piston pin bearings and the exterior of the plunger; and means for securing the follower to the piston member. 115

2. A self-lubricating plunger for pumps and the like, comprising a hollow piston member having a working head and a skirt of reduced diameter, said skirt being provided with piston pin bearings having passages adapted to conduct lubricant to the bores thereof; an inverted hollow follower telescoping over said skirt to provide a substantially closed hollow plunger adapted to contain lubricant, said follower having lu 125 130

bricant passages affording communication between said piston pin bores and the exterior of the plunger; yieldable packing interposed between the follower wall and the head of
5 said piston member; and means for adjustably securing said follower to said piston member.

3. A self-lubricating plunger for pumps and the like, comprising a hollow piston
10 member having a working head and a skirt of reduced diameter, said skirt being provided with piston pin bearings having passages adapted to conduct lubricant to the bores thereof; an inverted hollow follower
15 having a conical top wall provided with a central opening to accommodate a connecting rod, telescoping over said skirt to provide a substantially closed hollow plunger adapted to contain lubricant, said follower
20 also having lubricant passages affording communication between said piston pin bores and the exterior of the plunger; yieldable packing interposed between the follower wall and the head of said piston member;
25 and means for adjustably securing said follower to said piston member.

In testimony whereof I affix my signature.
CHARLES I. LONGENECKER.
